(57) **CLAIM**

The ornamental design for a lighting fixture, as shown and described.

DESCRIPTION

FIG. 1 is a perspective view of a lighting fixture showing a first embodiment of the new design. This fixture has mirror image symmetry along a vertical imaginary plane that bisects the canopy. The glass and lamp base each have a circular horizontal cross-section, and the canopy has a circular vertical cross-section. The lamp base has three-way, one hundred twenty degree overall rotational symmetry.

FIG. 2 is a front elevation view of the lighting fixture of FIG. 1.

FIG. 3 is a left side elevation view of the lighting fixture of FIG. 1, the right side elevation view being a mirror image of the left side elevation view.

FIG. 4 is a bottom plan view of the lighting figure of FIG. 1.

FIG. 5 is a perspective view of a lighting fixture showing a second embodiment of the new design. This fixture has mirror image symmetry along a vertical imaginary plane that bisects the canopy. The glass and lamp base each have a circular horizontal cross-section, and the canopy has a circular vertical cross-section. The lamp base has three-way, one hundred twenty degree overall rotational symmetry.

FIG. 6 is a front elevation view of the lighting fixture of FIG. 5.

FIG. 7 is a left side elevation view of the lighting fixture of FIG. 5, the right side elevation view being a mirror image of the left side elevation view; and,

FIG. 8 is a bottom plan view of the lighting figure of FIG. 5.

The dashed lines on the drawings depict portions of the lighting fixture that form no part of the claimed design.
